Attorneys.

UNITED STATES PATENT OFFICE

HOMER W. JONES, OF ELMHURST, NEW YORK, ASSIGNOR TO NATIONAL CARBON COMPANY, INC., A CORPORATION OF NEW YORK

FOCUSING FLASH LIGHT

Application filed July 12, 1923. Serial No. 651,149.

This invention relates to flashlights and particularly to focusing flashlights adapted to project a concentrated or a diffused beam of light as desired.

- 5 To obtain a wider range of illumination from flashlights it has been the practice to alter the spread of a reflected beam of light by adjusting the lamp and the reflector relatively to one another. The focusing mechanisms heretofore employed generally require 10 one hand to hold the flashlight and another to manipulate the adjusting device and, usually having parts thereof disposed outside the outline of the flashlight casing, are liable 15 to get out of adjustment by engaging other objects. The principal object of this invention is to provide an improved focusing mechanism for adjusting the lamp and the reflector relatively to one another which may 20 be located within the outline of the flashlight casing and which may be readily manipulated by the same hand that holds the flashlight. Another object is to provide a focusing mechanism that may be entirely 25 supported by a removable head of a flashlight casing.

The above and other objects and the novel features of this invention will be apparent from the following description, taken with 30 the drawings, in which:

Fig. 1 is a side elevation view, with a portion broken out, illustrating an improved flashlight embodying this invention; and

Fig. 2 is an enlarged central sectional view 35 of the head end of the same.

Broadly speaking, an improved focusing mechanism embodying this invention comprises an operating device or wheel mounted within a flashlight casing and having a portion 40 of its periphery exposed by a slot in said casing. The operating wheel may be rotatable about an axis extending lengthwise of the casing, desirably about the reflector axis, and is connected to a lamp holder or reflector 45 by mechanism for converting the rotary motion of the wheel to rectilinear motion, whereby the lamp and the focus of the reflector may be adjusted relatively to one another. In a desirable embodiment of the 50 invention as herein disclosed the reflector

is stationary while the lamp and the lamp holder are adjustable along the reflector axis by a wheel that has a resiliently mounted threaded hub part which bears against a fixed support in the casing and is rotatable in a fixed plane perpendicular to the reflector axis, the threaded hub interfitting with a similarly threaded part of the lamp holder and also constituting a cushioned abutment and contact for the battery and its center contact.

Referring to the drawing, the improved flashlight comprises a suitable casing of tubular sheet metal or other material, the bottom part C of which is adapted to contain a battery B supported by the usual spring E' in the removable end cap E. The upper end or head H of the casing is removably coupled to the bottom part C by interfitting threads 10, and carries the stationary parabolic reflector R, the adjustable incandescent lamp L and the associated focusing mechanism, whereby the head and these parts may be removed as a unit from the bottom part of the casing to simplify assembly and inspection. A standard non-focusing flashlight may thus be converted into a focusing type by merely substituting a focusing head for the head of the non-focusing flashlight. The usual removable lens ring J holds the 80 cover glass G and the gasket F in place against the front end of the head and reflector.

The lamp L is carried by a threaded part 11 of a lamp holder that is movable by a wheel W along the axis of the reflector through an axial opening 12 in the reflector. The wheel W is freely rotatable a limited number of turns in either direction about the reflector axis and has a minor segmental portion of its periphery projecting out through a circumferentially extending slot 13 in a depression 13' in the wall of the head whereby rotative force may be applied thereto by the thumb or a finger of the hand holding the flashlight. As shown, the diameter of the wheel may be nearly equal to the internal diameter of the head containing it, only a slight clearance being necessary for operation and purposes of assembly. To facilitate 100

- its operation, the periphery of the wheel may be knurled, and the slot is desirably only slightly larger than the exposed or projecting part of the wheel so that the latter practically closes the slot. The wheel W may be operatively connected to the lamp holder by any suitable mechanism that will convert its rotary motion into rectilinear motion and apply the latter to the lamp holder. A desirable mechanism comprises a threaded conductive stem 14 that is secured to said holder and engages in the internally threaded cavity 15 of a nut 16 secured to the wheel W and forming the hub thereof. The wheel W is rotatable in a fixed plane perpendicular to the reflector axis and may be held in this position by a helical spring P that bears against an inner shoulder 17 on the reflector and against the bottom 18' of a cup-shaped shell 18 secured to the lamp holder, the pressure being transmitted through the stem 14 and hub 16 to a shoulder 16' on the latter which is thereby held against a fixed support A within the head. The spring P also offers sufficient resistance to the turning of the stem 14 and lamp holder with the wheel when the latter is rotated, but an additional key may be provided between the lamp holder and reflector.
- 30 The parts 11 and 18 of the lamp holder with the interposed insulating washers 19 and 19' may be secured together and to the stem 14 by an expanded end 20' of a reduced part 20 on said stem. The reduced part 20 extends through and is spaced from a central opening 18'' in the bottom of the shell 18, and its upper end 20' is engageable by the center lamp contact L'.
- 35 The hub 16 is desirably of conductive material and has a reduced part 21 that projects through and below a central aperture 22 in the support A to provide a rotatable contact for engaging the central terminal B' of the battery. This rotatable contact may have a slightly convex surface and is advantageous because its rotary wiping action keeps the contacting surfaces clean, resulting in a low resistance at the point of contact. The hub 16, which may yield against the pressure of the spring P, thus also constitutes a cushioned or resilient abutment for the front end of the battery which maintains a closed circuit at this point. The wheel, except its hub, is non-conducting and may be made of rigid fiber, whereby the current-conducting parts of the mechanism are effectively insulated from the casing, where the latter is made of metal.
- 40 The support A may consist of a disk of rigid insulating material such as fiber and may be held in fixed position against an internal bead 23 by a removable split spring ring 24. A metal contact ring 25 is secured to the bottom side of the support A by rivets 26, 26', the latter also securing the lower end

of an insulation-covered conductor 27 to said support and electrically connecting it to said ring. The upper exposed end 27' of the conductor 27 is in electrical contact with the inner surface of the reflector. The contact ring 25 or the rivets 26, 26' are engageable by the upper end of a circuit closing conductor 28 which may be operated by the usual switch S mounted on the part C of the casing. The construction is desirably such that when the head H is screwed firmly onto the casing body C, the depression 13' and the switch S will be substantially in line, and the battery, lamp and reflector will have a common axis.

45 The current for lighting the lamp has the following path: battery terminal B', hub 16, stem 14 and reduced end 20, center lamp contact L', lamp filament, outer lamp contact L'', lamp holder parts 11 and 18, spring P, reflector R, conductor 27, rivet 26', ring 25, conductor 28, switch S, casing C, end cap E, spring E' to the bottom or other terminal of the battery. Rotation of the wheel W in one direction feeds the stem 14 and the lamp holder and lamp carried thereby along the reflector axis in one direction and rotation of the wheel in the reverse direction moves the lamp holder and lamp in the opposite direction along the reflector axis a concentrated beam being reflected when the lamp filament is substantially at the focus of the reflector, and diffused illumination being delivered when the filament is in front of or behind the focal point. The same hand that holds the flashlight may operate the switch S and the focusing wheel W which, being entirely within the outline of the casing, will not accidentally get out of adjustment, thereby eliminating special means for locking the focusing mechanism.

50 The operating device or wheel that projects through the slot 13 may be of different form or smaller size than shown and mounted in the casing on an axis parallel to the reflector axis, the lamp holder and the means connecting it to the operating wheel may be of different construction than illustrated, and other changes may be made in the flashlight disclosed without departing from the spirit of this invention.

55 I claim:

1. In a flashlight, the combination of a reflector, an incandescent lamp coaxial therewith, a casing for said lamp and said reflector, and means whereby said lamp and said reflector may be adjusted relatively to one another to vary the spread of the reflected beam comprising a wheel rotatable in a fixed plane about the axis of said reflector, said casing having an aperture exposing a portion 125 of said wheel for manipulation.

2. In a flashlight, the combination of a reflector, an incandescent lamp coaxial therewith, a casing enclosing said reflector and said lamp and having an aperture in its wall, and 130

means whereby said lamp and said reflector may be adjusted relatively to one another to vary the spread of the reflected beam comprising a wheel projecting from said casing through said aperture and rotatable about an axis extending longitudinally of the reflector axis, said aperture being substantially closed by a portion of the periphery of said wheel.

3. In a flashlight, the combination of a stationary reflector, an incandescent lamp movable along the axis of said reflector, a casing for said lamp and said reflector, and means whereby said lamp may be adjusted relatively to said reflector comprising a lamp holder, a wheel rotatable independently of said lamp holder about an axis extending longitudinally of the reflector axis, and means providing a threaded connection between said wheel and said lamp holder, said casing having an opening exposing a portion of said wheel for manipulation.

4. In a flashlight, the combination of a fixed reflector, an incandescent lamp movable along the axis of said reflector, a casing enclosing said lamp and said reflector, and means whereby said lamp may be adjusted relatively to said reflector to vary the beam of light comprising a wheel adjustable relatively to said lamp and rotatable about said reflector axis, said casing having a slot exposing and substantially closed by a portion of the periphery of said wheel.

5. In a flashlight, the combination of an incandescent lamp, a reflector therefor, a casing for said lamp and said reflector, and means comprising a wheel whereby said lamp and said reflector may be adjusted relatively to one another, said casing having a depression and an opening in said depression exposing a portion of the peripheral edge of said wheel for manipulation.

6. In a flashlight, the combination of a lamp, a reflector therefor, a casing for said lamp and said reflector, a fixed support in said casing, and means whereby said lamp and said reflector may be adjusted relatively to one another to vary the spread of the beam of light comprising a rotatable device bearing against said support in the direction of its axis of rotation, said casing having an opening exposing a portion of said device for manipulation.

7. In a flashlight, the combination of an incandescent lamp, a reflector therefor, a casing for said lamp and said reflector, a fixed support in said casing, and means whereby said lamp and said reflector may be adjusted relatively to one another to vary the spread of the beam of light comprising a wheel having a conductive hub bearing against said support, said casing having an opening exposing a non-conducting peripheral portion of said wheel for manipulation.

8. In a flashlight, the combination of a

stationary reflector, an incandescent lamp movable along the axis of said reflector, a casing enclosing said lamp and said reflector, a support in said casing, means whereby said lamp may be adjusted relatively to said reflector comprising a spring urging said lamp toward said support, and a wheel between said reflector and said support having a hub operatively connected to said lamp and bearing against said support, said casing having an opening exposing a portion of the periphery of said wheel for manipulation.

9. In a flashlight, the combination of a casing, an incandescent lamp, a reflector therefor, a battery having a central terminal, such reflector, lamp and battery being coaxially arranged in said casing, means in said casing adjustable axially relatively to said lamp whereby said lamp and said reflector may be adjusted relatively to one another, and a fixed support in said casing for such adjusting means having a central aperture through which the terminal of said battery may be connected in circuit with said lamp.

10. In a flashlight, the combination of a casing, an incandescent lamp, a reflector therefor, a battery, such reflector, lamp and battery being coaxially arranged in said casing, means rotatable independently of said reflector about an axis extending longitudinally of said casing whereby said lamp and reflector may be adjusted relatively to one another, a support for said rotatable means between said rotatable means and said battery, said support having an aperture, and means extending through said aperture connecting said battery in circuit with said lamp.

11. In a flashlight, the combination of a casing, an incandescent lamp, a reflector therefor, a battery having a central terminal, such reflector, lamp and battery being coaxially arranged in said casing, a wheel in said casing whereby said lamp and said reflector may be adjusted relatively to one another, and a fixed support for said wheel between said lamp and said battery, said support having an aperture and said wheel having a hub in said aperture in circuit with said battery terminal.

12. In a flashlight, the combination of a reflector, a lamp, means whereby said reflector and said lamp may be adjusted relatively to one another to vary the spread of the reflected beam, a battery in circuit with said lamp, a casing containing said battery and having a removable head carrying said reflector and lamp and such adjusting means, a cover glass secured to one end of said head in front of said reflector, and a support for such adjusting means secured in the opposite end of said head.

13. In a flashlight, the combination of a

- reflector, a lamp movable axially of said reflector, means whereby said lamp may be adjusted relatively to said reflector to vary the spread of the reflected beam, a battery in circuit with said lamp, a casing containing said battery and having a removable head carrying said reflector and lamp and such adjusting means, a conductor in said head in circuit with said lamp, a switch carried by 6 said casing, and a second conductor connected to said switch and adapted to engage the first mentioned conductor when said head is assembled in place.
14. In a flashlight, the combination of a reflector, an incandescent lamp, a holder for said lamp having a threaded part united thereto, a support independent of said reflector, and a rotatable element bearing against said support and having a threaded 15 part cooperating with the threaded part of said holder to adjust said lamp along the axis of said reflector.
15. In a flashlight, the combination of a casing; a reflector; an incandescent lamp; a holder for said lamp having a threaded part united thereto; said reflector, lamp and holder being coaxially arranged in said casing; a support within said casing; a rotatable element mounted in said casing, bearing against 20 said support and having a threaded part cooperating with the threaded part of said holder to adjust said lamp along the axis of said reflector, said casing having a slot exposing a portion of said element for manipulation.
16. In a flashlight, the combination of a reflector; an incandescent lamp; a lamp holder; a spring adapted to move the lamp holder inwardly axially of the reflector; an exteriorly threaded stem secured to the inner end 40 of said lamp holder; a casing having a head carrying said reflector, lamp, and lamp holder, and having a slot in its side wall; an insulating apertured support mounted in said head; a threaded nut fitting said stem and bearing against said support; a battery in 45 said casing conductively connected to said nut through the aperture in said support; and a wheel mounted on said nut and having a peripheral portion exposed by said slot.
17. In a flashlight, the combination of a battery having a contact, an incandescent lamp, a reflector therefor, and means for adjusting said lamp and said reflector relatively to one another to vary the reflected light, such adjusting means comprising a conductive member, a spring pressing said 55 member against said contact, maintaining a closed circuit therat and operative to wipe said contact during the operation of such adjusting means.
18. In a flashlight, the combination of a battery having a center contact, an incan- 60 descent lamp, a reflector therefor, and means for adjusting said lamp and said reflector relatively to one another to vary the reflected light, such adjusting means comprising a cushioned abutment having a contact engageable by said battery contact and operative to wipe the latter during the operation of such adjusting means. 70
19. In a flashlight, the combination of a battery carrying a center contact; an incandescent lamp; a reflector therefor; said battery, lamp and reflector having a common axis; and means for adjusting said lamp and said reflector relatively to one another to alter the reflected light; such adjusting means comprising an abutment rotatable independently of said lamp about said common axis and having a wiping contact engageable by said battery contact. 75
20. In a flashlight, the combination of a battery carrying a center contact; an incandescent lamp; a reflector therefor; said battery, lamp and reflector having a common axis; and means for adjusting said lamp and said reflector relatively to one another to alter the reflected light; such adjusting means comprising a cushioned contact abutment bearing against such battery contact and rotatable about said common axis. 80
21. In a flashlight, the combination with a reflector, an incandescent lamp, and a battery contact in axial alignment; of means for adjusting said lamp and said reflector relatively to one another, to alter the spread of the reflected light beam, such adjusting means comprising a contact bearing against said battery contact and rotatable independently of said lamp about the common axis of such reflector and lamp. 85
22. A focusing electric lamp comprising the combination of an incandescent bulb member; a reflector member having an aperture through which said bulb projects; one of said members being adjustable relatively to the other to vary the spread of the light from said lamp; a casing for said members having an opening in a wall thereof; and means for moving such adjustable member comprising a wheel rotatably mounted within said casing and having a segmental portion of its periphery projecting through said opening for manipulation from the outside of said casing. 90
23. A focusing electric lamp according to claim 22, wherein said aperture is coaxial with the main axis of said reflector, said bulb is adjustable along said axis, and the major portion of said wheel is within said casing and only minor segmental portions of its periphery are exposed by said opening for manual engagement to adjust said bulb. 100
24. A focusing electric lamp according to claim 22, wherein said casing comprises a head detachably coupled to a body, said open- 105

ing is in said head, and said wheel is rotatably mounted in said head and is operatively connected to the adjustable member by means adapted to convert the rotary motion of the
5 wheel into rectilinear motion.

In testimony whereof, I affix my signature.
